US0D1057767S

(12) **United States Design Patent** (10) **Patent No.:** **US D1,057,767 S**
(45) **Date of Patent:** **** Jan. 14, 2025**

(54) **PORTION OF DISPLAY PANEL OR SCREEN WITH AN ICON**

(71) Applicant: **SONY GROUP CORPORATION**,
Tokyo (JP)

(72) Inventors: **Chikako Yoshinaka**, Kanagawa (JP);
Chihiro Aoshima, Tokyo (JP)

(73) Assignee: **SONY GROUP CORPORATION**,
Tokyo (JP)

(**) Term: **15 Years**

(21) Appl. No.: **29/873,745**

(22) Filed: **Apr. 6, 2023**

(30) **Foreign Application Priority Data**

Oct. 11, 2022 (JP) ..... 2022-021926 D

(57) **CLAIM**

The ornamental design for a portion of a display panel or screen with an icon as shown and described.

DESCRIPTION

The patent or application file contains at least one drawing executed in color. Copies of this patent or patent application publication with color drawing(s) will be provided by the Office upon request and payment of the necessary fee.

FIGURE is a front view of a portion of a display panel or screen with an icon showing our new design.

The dot-dash broken lines constituting a portion of a display panel or screen defining the boundaries of the claimed design form no part of the claimed design.
